ABSTRACT OF THE DISCLOSURE

The application describes apparatus for utilizing the two baseband signals V_1 and V_2 , derived from a quaternary differential phase detector, to regenerate a differential-phase-modulated PCM signal.

In accordance with the invention, a translator converts signals V_1 and V_2 into a single signal, $\mu_1 + \mu_2$, which drives a voltage-sensitive oscillator. The translator includes a signal divider which divides the V_1 signal into two components. One component constitutes the μ_1 signal. The other component and the V_2 signal are coupled to a sign generator which generates the μ_2 signal such that

$$\text{sgn. } \mu_2 = -(\text{sgn. } V_1)(\text{sgn. } V_2)$$

The μ_1 and μ_2 signals are then combined in an adder to produce the regenerator drive signal. Amplifiers are also included to adjust the relative amplitudes of μ_1 and μ_2 to yield the required differential phase shift.

This invention relates to regenerative repeaters for use in four-state, differential-phase-modulated PCM signals, also referred to as differentially coherent phase-shift-keyed (DCPSK) modulation.

BACKGROUND OF THE INVENTION

In the copending application by W. D. Warters, Ser. No. 568,893, filed July 29, 1966, and assigned to applicant's assignee, there is described a two-state, differential-phase-modulated PCM communication system. In this system, the high frequency signal is frequency modulated above and below some reference frequency to produce an equivalent phase modulation of either +90 degrees or -90 degrees. The various advantages of such a system are described by Warters, as are various arrangements for detecting and regenerating the signal.

It is well known that more efficient use can be made of the frequency spectrum by increasing the number of possible signal states from two to more than two. For example, a four-state, or quaternary system, permits the combining and transmission, along the same transmission system, of two binary-encoded signals. In general, a 2^n -state system would permit the multiplexing of n binary-encoded signals.

SUMMARY OF THE INVENTION

The present invention relates to apparatus for regenerating a quaternary differential-phase-modulated (DPM) signal in which the differential phase shift between signals in adjacent time slots is either $\pi/4$, $-\pi/4$, $3\pi/4$ or $-3\pi/4$ radians.

In the copending application by W. H. Hubbard, Ser. No. 659,209, filed Aug. 8, 1967, there is described a quaternary differential phase detector which generates a pair of output signals V_1 and V_2 whose polarities are indicative of the four possible phase states of the signal. In particular, output signal V_1 is indicative of the sign ($\pm$) of the phase deviation, while the polarity of signal V_2 is indicative of the amplitude ($\pi/4$ or $3\pi/4$ radians) of the phase deviation.

The apparatus to be described herein, includes a remodulator which generates the quaternary DPM signal, and a translator which converts signals V_1 and V_2 to a second pair of signals, μ_1 and μ_2 , capable of operating the remodulator. Since, as explained hereinabove, the output from the quaternary differential phase detector consists of two signals V_1 and V_2 , it is the function of the translator to utilize the information contained in these signals and to generate a single signal capable of driving the remodulator.

In accordance with the present invention, the translator converts signals V_1 and V_2 to a second pair of signals μ_1 and μ_2 such that

$$\text{sgn. } \mu_1 = \text{sgn. } V_1$$

and

$$\text{sgn. } \mu_2 = -(\text{sgn. } V_1)(\text{sgn. } V_2)$$

where $\mu_1 + \mu_2$ is a function of the required differential phase shift.

In the illustrative embodiment of the invention, to be described in greater detail hereinbelow, the remodulator is a voltage-sensitive oscillator whose instantaneous frequency is varied in response to an input voltage applied thereto. Assuming, for purposes of illustration, an approximately linear voltage-frequency characteristic for the remodulator, proper regeneration occurs when $\mu_1 + \mu_2$ is linearly proportional to the differential phase shift. This is obtained by making $|\mu_1| = 2|\mu_2|$.

An illustrative translator comprises a power divider, a sign generator and a signal adder. The power divider divides the signal into two components. One component is amplified to become the μ_1 signal. The other component is coupled to the sign generator, along with signal V_2 , to generate the μ_2 signal. The two signals are then summed in the adder and coupled to the remodulator. The amplitude and polarity of each of the translated signals μ_1 and μ_2 are separately adjusted in accordance with the requirements of the remodulator to produce the required phase deviation.

These and other objects and advantages, the nature of the present invention, and its various features, will appear more fully upon consideration of the various illustrative embodiments now to be described in detail in connection with the accompanying drawings.

BRIEF DESCRIPTION OF THE DRAWINGS

FIG. 1 shows, in block diagram, a portion of a repeater for use in a quaternary differential-phase-modulated PCM system including a quaternary differential phase detector and regenerator, a translator and a remodulator;

FIG. 2, included for purposes of explanation, shows the four possible phase changes the signal can experience between successive sampling intervals;

FIG. 3 shows, in block diagram, the details of a translator and a remodulator in accordance with the invention;

FIG. 4 shows the circuit details of an illustrative sign generator for use in the translator.

DETAILED DESCRIPTION

Referring to the drawings, FIG. 1 shows, in block diagram, a portion of a PCM repeater to which the invention relates. Included in FIG. 1 are a quaternary differential phase detector and regenerator 10, a translator 11, and a remodulator 12. In principle the repeater can be adapted to regenerate any four-level differential-phase-modulated PCM signal. In particular, however, the four-level signal to which the present invention relates is characterized by a constant-amplitude, alternating current wave whose phase is shifted by either $\pi/4$, $-\pi/4$, $+3\pi/4$ or $-3\pi/4$ radians between successive time slots. The signal is represented in FIG. 2 by a vector v , depicting the

signal phase at any sampling instant, and by vectors 1, 2, 3 and 4, depicting the four possible phase states at the next sampling instant. For example, the phase can deviate by $\pi/4$ radians, as represented by vector 1, or by any of the other amounts indicated above, as represented by vectors 2, 3 and 4. The function of the arrangement of FIG. 1 is to determine the magnitude and sign of this phase shift and to regenerate the signal.

In the copending application by Hubbard, referred to hereinabove, the quaternary phase detector is described in detail. For the purpose of the present discussion it is sufficient to note merely that the detector generates a pair of output signals V_1 and V_2 as summarized in Table I.

TABLE I

Differential phase shift	V_1	V_2
$\pi/4$	1	1
$3\pi/4$	1	-1
$-\pi/4$	-1	1
$-3\pi/4$	-1	-1

As can be seen, the polarity of output signal V_1 is indicative of the sign ($\pm$) of the differential phase shift, while the polarity of output signal V_2 is indicative of the amplitude ($\pi/4$ or $3\pi/4$) of the differential phase shift. Accordingly, these two signals contain all of the information required either to reconstruct the original baseband, or to regenerate the high frequency signal. The absolute amplitudes of signals V_1 and V_2 can be arbitrarily adjusted by the inclusion of an amplifier in either or both signal paths.

The manner in which the information contained in signals V_1 and V_2 is used depends upon the particular application at hand. In accordance with the present invention, which relates to regenerative repeaters, the information contained in signals V_1 and V_2 is used to regenerate the differential phase modulated, alternating current signal. The manner in which this is accomplished is based upon the fact that a frequency varying signal $f(t)$ undergoes a phase shift $\Delta\varphi$, measured relative to a reference signal at frequency f_0 , that is given by

$$\Delta\varphi = 2\pi \int_{t_1}^{t_2} [f(t) - f_0] dt$$

where the integration is over the time interval $t_2 - t_1$. In a PCM system, the integration is taken over a period equal to one time slot.

Thus, means are provided for combining signals V_1 and V_2 in such a manner so as to produce a single signal which, when applied to the remodulator, is capable of regenerating the desired alternating current signal.

FIG. 3 shows, in block diagram, details of a translator and a remodulator in accordance with the invention. As depicted in FIG. 3, remodulator 12 comprises an FM-deviator 30 which can be any variety of voltage-controlled oscillator, such as a tunnel diode oscillator, whose frequency of oscillation is a function of the bias applied thereto. The unmodulated oscillator frequency is typically established by a bias source 34. Frequency modulation is produced by signal $\mu_1 + \mu_2$ coupled to deviator 30 in a manner to vary its instantaneous bias an amount sufficient to produce the desired phase deviation $\Delta\varphi$. Assuming, for purposes of discussion, a linear frequency versus bias characteristic for the oscillator, the relative amplitude and the polarity of the driving signal $\mu_1 + \mu_2$ for each of the four possible phase states is given in Table II.

TABLE II

Differential phase shift:	$\mu_1 + \mu_2$
$\pi/4$	+1
$3\pi/4$	+3
$-\pi/4$	-1
$-3\pi/4$	-3

A translator for generating the required drive signal, as illustrated in FIG. 3, comprises a divider 31, a sign generator 32 and an adder 33. An amplifier 35 is also shown for reasons which will be explained in greater detail hereinbelow.

In operation, signal V_1 is divided by divider 31 into two components. One component of V_1 constitutes the μ_1 signal. The other component is coupled to sign generator 32 along with signal V_2 . The sign generator operates upon signals V_1 and V_2 to produce a signal μ_2 whose polarity (sign) depends upon the polarities (signs) of both V_1 and V_2 .

Signals μ_1 and μ_2 are then combined in adder 33 to produce the remodulator drive signal $\mu_1 + \mu_2$.

The translator shown in FIG. 3 also includes an amplifier 35 to adjust the amplitude of μ_1 relative to μ_2 . In the particular embodiment of the invention described herein, $|\mu_1| = 2|\mu_2|$. In addition, the sign of μ_2 is made to be negative when V_1 and V_2 have the same polarities, and positive when V_1 and V_2 have opposite polarities. When both of these conditions are met, the relationship between the phase deviation and the various signals is as shown in Table III.

TABLE III

Differential phase deviation	V_1	V_2	μ_1	μ_2	$\mu_1 + \mu_2$
$\pi/4$	1	1	2	-1	+1
$3\pi/4$	1	-1	2	+1	+3
$-\pi/4$	-1	+1	-2	+1	-1
$-3\pi/4$	-1	-1	-2	-1	-3

It will be noted that the $\mu_1 + \mu_2$ signals satisfy the amplitude and polarity requirements of the remodulator drive signal, as given in Table II.

One illustrative translator arrangement for generating the remodulator drive signal $\mu_1 + \mu_2$ is given in FIG. 4, which shows the circuit details of divider 31, adder 33 and sign generator 32. Signal V_1 , derived from the quaternary phase detector, is coupled to the divider wherein it is divided into two components. One of these components is coupled to the adder circuit as signal μ_1 . An amplifier 35 is advantageously included in the μ_1 signal circuit to maintain the proper level of the μ_1 signal. The other V_1 component is coupled to the sign generator along with signal V_2 .

The sign generator examines the polarity of the V_1 and V_2 signals. If they are the same, both positive or both negative, an output signal of one polarity is generated. If, however, the V_1 and V_2 signals are of different polarities, an output signal of opposite polarity is produced. In the particular illustrative embodiment shown in FIG. 4, the polarity of output signal μ_2 is negative when the signs of V_1 and V_2 are the same, and positive when the signs of V_1 and V_2 are different. That is,

$$\text{sgn. } \mu_2 = -(\text{sgn. } V_1)(\text{sgn. } V_2) \quad (1)$$

Basically, the sign generator is a modified "Goto-pair," comprising a pair of series-connected diodes 40 and 41, and associated biasing circuits. (For a detailed description of the Goto-pair circuit, see "Some New High-Speed Tunnel-Diode Logic Circuits," by M. S. Axelrod et al., I.B.M. Journal, April 1962, pp. 158-169.)

Each of the diodes 40 and 41 is characterized by a current-voltage curve which includes first and second positive resistance regions, and a negative resistance region therebetween. The diodes are biased, through the lengths of transmission line 42 and 43, at operating points within their first positive resistance regions. A second biasing circuit, connected to the common junction 45 between the two diodes is used to establish a slight imbalance in the diode biases for reasons which are explained hereinbelow.

In operation, a balanced timing pulse, synchronized with the bit rate of the differential phase modulated signal, is applied across the diodes. The polarity and amplitude

of the timing pulse is such as to drive the operating points of both diodes towards their negative resistance regions. Depending upon which one of the diodes reaches its negative resistance region first, one or the other diode switches to an operating point in its second positive resistance region, producing either a positive or a negative output pulse at their common junction 45.

In accordance with the present invention, the biases are adjusted such that in the absence of any other signals, diode 41 switches in response to a timing pulse, producing a positive output signal. In order to produce a negative output pulse, means, comprising a second pair of diodes 46 and 47 and resistor 48, are provided. The second pair of diodes, which are connected series-aiding across diode 40, are poled oppositely to diode 40 and are connected at their common junction 49 to an adjustable tap on resistor 48. A bias circuit 50 adjusts the biases across diodes 46 and 47.

In operation, signals V_1 and V_2 are connected, respectively at opposite ends of resistor 48. When both V_1 and V_2 are positive, current flows from resistor 48 through diode 46, to diode 40 and, hence, to ground through the adder circuit 33. This additional current through diode 40 increases the voltage across diode 40, thereby causing it to switch in response to a timing pulse, instead of diode 41, and to produce a negative output pulse. Similarly, when both V_1 and V_2 are negative, current is diverted away from diode 41 and towards resistor 48 through diode 47. The effect of this is to reduce the bias across diode 41 relative to the bias across diode 40 so that the latter diode switches in response to the timing pulse, thereby producing a negative output pulse.

If, on the other hand, V_1 and V_2 are of opposite polarity, the tap on resistor 48 is adjusted so that no net current flows towards resistor 48 to disturb the bias settings on diodes 40 and 41. As a result, diode 41 switches, thereby producing a positive output pulse. Thus, the translator illustrated in FIG. 4 satisfies the requirements of Equation 1 in that μ_2 is positive when the polarities of V_1 and V_2 are different, and negative when the polarities of V_1 and V_2 are the same.

Having generated the two signals μ_1 and μ_2 , they are added in adder 33 to produce the remodulator drive signal $\mu_1 + \mu_2$.

In the particular situation where the voltage-frequency characteristic of the remodulator is linear, the gain of amplifier 35 is adjusted such that $|\mu_1| = 2|\mu_2|$. Other voltage-frequency remodulator characteristics will, of course, require other adjustments to regenerate the proper differential-phase-modulated signal.

It should be noted that the indicated polarities of the various signals V_1 , V_2 , μ_1 and μ_2 are merely illustrative. By the simple expedient of reversing diode connections, or by the inclusion of amplifiers, other combinations of signal polarities can be devised to produce the required regenerated output signal. It should also be noted that the specific translator and remodulator circuits shown are merely intended to be illustrative, and that other circuits can just as readily be used. For example, instead of separately regenerating the V_1 and V_2 signals immediately following detection, as is done in the copending application by Hubbard, the V_1 signal can be regenerated by means of a regenerator located in the μ_1 circuit between divider 31 and adder 33, while the sign generator 32 itself also doubles as a regenerator for the μ_2 signal. In addition, it is understood that amplifiers, which have not been shown, would typically be included to control the amplitude of the various signals. Thus, in all cases it is understood that the above-described arrangement is illustrative of but one of the many possible specific embodiments which can represent applications of the principles of the invention. Numerous and varied other arrangements can readily be devised in accordance with these principles to those skilled in the art without departing from the spirit and scope of the invention.

What is claimed is:

1. For use in a quaternary phase modulated communications system; a translator for converting a first pair of signals V_1 and V_2 into a second pair of signals μ_1 and μ_2 such that

$$\text{sgn. } \mu_1 = \text{sgn. } V_1$$

$$\text{sgn. } \mu_2 = -(\text{sgn. } V_1)(\text{sgn. } V_2)$$

and for summing said μ_1 and μ_2 signals; said translator including:

a signal divider for dividing said V_1 signal into two components; a sign generator for generating said μ_2 signal; and an adder for adding said μ_1 and said μ_2 signals to form an output signal $\mu_1 + \mu_2$; means for coupling one of said V_1 components to said adder, said one component constituting said μ_1 signal; means for coupling the other of said V_1 components to said sign generator; means for coupling said V_2 signal to said sign generator; means for coupling signal μ_2 between said sign generator and said adder; and means for extracting said output signal $\mu_1 + \mu_2$ from said adder.

2. The apparatus according to claim 1 including: an oscillator whose output frequency varies in response to an externally applied signal; and means for applying said output signal $\mu_1 + \mu_2$ thereto, thereby frequency modulating said oscillator.

3. The apparatus according to claim 1 wherein said converting means includes a sign generator comprising: first and second diodes, each having a current-voltage characteristic which includes first and second positive resistance regions and a negative resistance region therebetween; said diodes being connected series-aiding and biased at operating points within their first positive resistance regions; means for applying timing pulses across said diodes of a polarity and amplitude sufficient to drive said diodes into their negative resistance regions, thereby causing one or the other of said diodes to switch to the second positive region of its current-voltage characteristic; characterized in that the bias applied to said diodes are different such that one of said diodes switches in response to said timing pulses in preference to the other of said diodes;

means, responsive to said signals V_1 and V_2 , for changing the relative bias across said diodes such that the other of said diodes switches in response to said timing pulse when the polarities of said signals V_1 and V_2 are the same; and means for coupling a signal out of said generator at the common junction between said diodes.

4. The sign generator according to claim 3 wherein a positive output signal is produced when V_1 and V_2 have different polarities;

and wherein a negative output pulse is produced when signals V_1 and V_2 have the same polarity.

5. In a quaternary differential-phase-modulated communication system, apparatus for regenerating an alternating current signal whose phase is shifted by either $\pi/4$, $-\pi/4$, $3\pi/4$ or $-3\pi/4$ radians during successive time intervals;

said apparatus including:

means for converting a first pair of signals V_1 and V_2 into a second pair of signals μ_1 and μ_2 such that

$$\text{sgn. } \mu_1 = \text{sgn. } V_1$$

and

$$\text{sgn. } \mu_2 = -(\text{sgn. } V_1)(\text{sgn. } V_2)$$

where the polarities of said V_1 and V_2 signals are indicative of the sign and magnitude, respectively, of the differential phase shift of said alternating current signal during said successive time intervals;

means for summing said μ_1 and μ_2 signals to produce an output signal $\mu_1 + \mu_2$;

an oscillator whose output frequency varies in response to an externally applied signal;

and means for applying said output signal thereto, thereby frequency modulating said oscillator.
